APPLE CELLING AND SLICING MACHINE HAVING A JUICE PASSAGEWAY

John E. Lindsay, Rochester, N. Y., assignor to F. B. Pease Company, Inc., Rochester, N. Y.

Application May 31, 1952, Serial No. 290,892

6 Claims. (Cl. 146—40)

This invention relates to machines for seed-celling and slicing apples and similar fruits and particularly to novel transmission and supporting means for the main spindles of such machines.

In preparing apples for cooking, canning, drying or deep freezing, it is customary, in commercial operation, to first pare and core the apples and then feed them into a machine where their seed-cells are removed and the apples are sliced radially into any desired number of segments. A common type of seed-celling and slicing machine comprises a spindle for receiving a succession of cored apples which move along the spindle to be successively seed-celled and sliced.

In the general type of seed-celling and slicing machine here under consideration, each apple is moved into partial engagement with the slicing knives and is held against rotation by such knives while a seed-celling knife carried by the spindle cuts out the seed-cells by rotation of the spindle. The apple is then pushed farther along the spindle to be fully sliced by the slicing blades.

In general, the spindles of the type of machine to which the present invention relates are mounted at their lower ends in bearings which are incorporated in or associated with transmission mechanism by means of which the spindle is rotated to effect the seed-celling operation. Since the seed-celling and slicing is effected along the spindle above the bearing and transmission mechanism much difficulty has heretofore been encountered with fruit juices seeping down into the transmission mechanism.

This problem has persisted despite provisions for packing and sealing the transmission bearings with conventional seals and packings. The present invention provides a transmission casing, spindle bearing and spindle arrangement which entirely eliminates this difficulty without relying upon the efficacy of conventional bearing seals and packings, although such seals may be used as an additional precaution.

In the arrangement of the present invention the objectionable seepage is drained off in a manner which precludes its entry into the interior of the transmission casing proper and before it reaches the usual bearing seal or packing. While a single complete embodiment of the principles of the present invention is set forth herein by way of example, it is to be understood that various modifications may be made without departing from the spirit of the invention, the scope of which is limited only as defined in the appended claims.

In the drawings:

Fig. 1 is a somewhat schematic fragmentary general elevational view of a seed-celling and slicing machine of the general type here under consideration;

Fig. 2 is a fragmentary cross-sectional view on the line II—II of Fig. 1 on an enlarged scale showing one form of the spindle bearing and transmission arrangement of the present invention; and

Fig. 3 is a fragmentary cross-sectional view on the line III—III of Fig. 2.

In the drawing like characters of reference denote like parts and, referring particularly to Fig. 1, the numeral 10 designates generally a portion of the framework of a seed-celling and slicing machine, Fig. 1 showing only so much of the machine generally as is necessary and helpful to a proper understanding of the present invention. A vertical fruit-impaling spindle is designated 11 and is supported at its lower end by a transmission mechanism, the casing of which is designated 12 in Figs. 1

and 2. A slicing knife ring or spider 13 is supported by framework 10 in such manner that it is disposed concentrically about spindle 11 in proximity to a conventional seed-celling knife 15 which is fixed to spindle 11. Slicing knife rings or spiders like that designated 13 in Fig. 1 are common in this art and representative showings thereof are found, for instance, in United States Letters Patent No. 2,496,637 and 2,509,781 to John W. Pease. In Fig. 1 the numeral 16 designates an arm whose left-hand end, as viewed in Fig. 1, rocks downwardly to move cored fruit downwardly along spindle 11.

The manner in which spindle 11 is mounted and supported for driving rotation at its lower end by the transmission means will now be described, reference being had particularly to Fig. 2. Transmission casing 12 is provided with a hub 20 which is coaxial with spindle 11 and serves as a support for a removable upper spindle bearing assembly.

A bearing cap 21 has a lower skirt portion 22 which 15 clamps about hub 20 by means of a split portion 23 and a bolt and nut clamp 24. A bushing 25 is pressed tightly into cap 21, and its lower portion projects downwardly into the annular space defined by skirt portion 22 of cap 21.

25 A bushing 28 is pressed tightly into the interior of hub 20 and the upper end of a sleeve shaft element 30 has rotatable bearing in bushing 28. A combined axial and radial thrust ball bearing 31 is mounted in the lower wall of transmission casing 12 coaxially with bushings 25 and 28, and the lower end of sleeve shaft 30 has bearing therein. A driven bevel gear 33 is fixed to sleeve shaft 30 in any desired manner for rotation jointly therewith.

30 A drive pin 35 is pressed transversely into sleeve shaft 30, and spindle 11 is notched at its lower end as at 36. Spindle 11 may be freely assembled from above by projecting it downwardly through bushing 25 and into sleeve shaft 30 to the position of Fig. 2, whereupon drive pin 35 causes joint rotation of sleeve shaft 30 and spindle 11.

35 Bevel gear 39 meshes with a bevel drive pinion 37 whose supporting shaft, indicated at 38 in Fig. 1, is journaled in transmission casing 12. Any suitable external drive means for shaft 38 may be provided.

40 It will be noted that the upper end of sleeve shaft 30 has an enlarged bore 40 which loosely receives the downwardly projecting portion of bushing 25. Further, spindle 11 is flattened as at 41 from a point above the bottom of bore 40 downwardly to the end of the spindle.

45 It will be seen from the foregoing that any seepage of fruit juices downwardly along shaft 11 will pass rather readily between shaft 11 and cap 21, where the clearance is slightly greater than a normal running fit, and will tend to pass downwardly along the running fit between shaft 11 and the interior of bushing 25, since the exterior of bushing 25 is pressed securely into cap 21. In prior art constructions this seepage would ordinarily pass downwardly into the transmission casing in one way or another.

50 In constructions generally like the one here under consideration the juices would seep between the wall of sleeve shaft 30 and the bore of bushing 28, this being a running bearing fit, and past experience has shown that packings and fluid seals have been of little help in preventing such seepage. Even if the initial efficiency of such a seal be fairly good, continued rotation wears the seal sufficiently to permit objectionable seepage. The harm which these juices cause to the drive means, particularly when they harden, is too well-known to require discussion.

55 It is obvious from a consideration of Fig. 2 that such juices as seep past the running fit between bushing 25 and spindle 11 fall freely through the interior of sleeve shaft 30, especially along the flattened portion of spindle 11 as indicated by the arrows in Fig. 2, and fall clear of the transmission casing beneath sleeve shaft 30.

60 A seal is interposed between the upper end of sleeve shaft 30 and hub 20 of casing 12, the seal being designated 42 in Fig. 2 and bearing against the top of bushing 28. However, from the standpoint of downward seepage of fruit juices, this seal is provided only as an extra precaution and, in normal operation, its presence will be of no practical significance.

65 What is claimed is:

1. In a seed-celling and slicing machine, a vertically extending rotary spindle, a seed-celling knife carried by said spindle, transmission means at the lower end of said spindle for supporting and rotating the same, a slicing spider concentric with said spindle, means for moving cored fruit downwardly along said spindle toward and past said seed-celling knife, said transmission means including a fixed casing and a vertical power driven hollow shaft journaled therein and adapted to receive the lower portion of said spindle and engage the same in rotary driving relationship, said transmission casing including a bushing at its upper end for bearing engagement with said spindle generally above said hollow shaft, the hollow interior of said shaft being enlarged at its upper end to receive the lower end of said bushing, said hollow shaft interior comprising a discharge opening at the bottom of said transmission means, said spindle having a longitudinal formation in its periphery extending from the vicinity of said hollow shaft interior enlargement to the lower end of the spindle to provide a free passageway for fruit juices.

2. In a fruit treating machine, a vertically extending rotary spindle adapted to receive cored fruit, transmission means at the lower end of said spindle for supporting and rotating the same, means for moving cored fruit downwardly along said spindle, said transmission means including a fixed casing and a vertical power driven hollow shaft journaled therein and adapted to receive the lower portion of said spindle and engage the same in rotary driving relationship, said transmission casing including a bushing at its upper end for bearing engagement with said spindle generally above said hollow shaft, the hollow interior of said shaft being enlarged at its upper end to receive the lower end of said bushing, said hollow shaft interior comprising a discharge opening at the bottom of said transmission means, said spindle having a longitudinal formation in its periphery extending from the vicinity of said hollow shaft interior enlargement to the lower end of the spindle to provide a free passageway for fruit juices.

3. In a seed-celling machine, a vertically extending rotary spindle, a seed-celling knife carried by said spindle, transmission means at the lower end of said spindle for supporting and rotating the same, means for moving cored fruit downwardly along said spindle to said seed-celling knife, said transmission means including a fixed casing and a vertical power driven hollow shaft journaled therein and adapted to receive the lower portion of said spindle and engage the same in rotary driving relationship, said transmission casing including a bushing at its upper end for bearing engagement with said spindle generally above said hollow shaft, the hollow interior of said shaft being enlarged at its upper end to receive the lower end of said bushing, said hollow shaft interior comprising a discharge opening at the bottom of said transmission means, said spindle having a longitudinal formation in its periphery extending from the vicinity of said hollow shaft interior enlargement to the lower end of the spindle to provide a free passageway for fruit juices.

4. In a seed-celling and slicing machine, a vertically extending rotary spindle, a seed-celling knife carried by

said spindle, transmission means at the lower end of said spindle for supporting and rotating the same, a slicing spider concentric with said spindle, means for moving cored fruit downwardly along said spindle toward and past said seed-celling knife, said transmission means including a fixed casing and a vertical power driven hollow shaft journaled therein and adapted to receive the lower portion of said spindle and engage the same in rotary driving relationship, said transmission casing including a bushing at its upper and for bearing engagement with said spindle generally above said hollow shaft, the hollow interior of said shaft being enlarged at its upper end to receive the lower end of said bushing, and the bearing surfaces of said spindle and the hollow interior of said shaft having a longitudinal passage therebetween extending downwardly from said hollow shaft interior enlargement to provide a discharge opening at the bottom of said transmission means.

5. In a fruit treating machine, a vertically extending rotary spindle adapted to receive cored fruit, transmission means at the lower end of said spindle for supporting and rotating the same, means for moving cored fruit downwardly along said spindle, said transmission means including a fixed casing and a vertical power driven hollow shaft journaled therein and adapted to receive the lower portion of said spindle and engage the same in rotary driving relationship, said transmission casing including a bushing at its upper end for bearing engagement with said spindle generally above said hollow shaft, the hollow interior of said shaft being enlarged at its upper end to receive the lower end of said bushing, and the bearing surfaces of said spindle and the hollow interior of said shaft having a longitudinal passage therebetween extending downwardly from said hollow shaft interior enlargement to provide a discharge opening at the bottom of said transmission means.

6. In a seed-celling machine, a vertically extending rotary spindle, a seed-celling knife carried by said spindle, transmission means at the lower end of said spindle for supporting and rotating the same, means for moving cored fruit downwardly along said spindle to said seed-celling knife, said transmission means including a fixed casing and a vertical power driven hollow shaft journaled therein and adapted to receive the lower portion of said spindle and engage the same in rotary driving relationship, said transmission casing including a bushing at its upper end for bearing engagement with said spindle generally above said hollow shaft, the hollow interior of said shaft being enlarged at its upper end to receive the lower end of said bushing, and the bearing surfaces of said spindle and the hollow interior of said shaft having a longitudinal passage therebetween extending downwardly from said hollow shaft interior enlargement to provide a discharge opening at the bottom of said transmission means.
